BANDING MECHANISM

Joseph A. Neumair, Hollis, N. Y., assignor to International Cigar Machinery Company, a corporation of New Jersey

Original application August 22, 1932, Serial No. 629,959. Divided and this application October 6, 1936, Serial No. 104,242

29 Claims. (Cl. 131—61)

This invention relates to wrapping and/or banding machines, more particularly a banding mechanism operating on cigars or other articles. The present application constitutes a division of my co-pending application S. N. 629,959, filed August 22, 1932, and which has matured as Letters Patent No. 2,077,431, issued April 20, 1937. The invention also relates to an improved package particularly for cigars, and an improved method of making such packages.

The principal object is to produce a simple yet efficient and high speed banding mechanism designed particularly for use with a wrapping mechanism, but capable of use alone, and which can be readily removed and replaced as a unit.

Since some cigar manufacturers prefer bands inside and others outside of the wrapper, the bander is designed to be selectively arranged to band either way.

One of the objects of the invention is the production of an improved band folding mechanism which does not release one end of the band while folding the other over it and which retains the folded and adhering ends during movement from banding position until the band ends have firmly adhered.

With these and other objects not specifically mentioned in view, the invention consists in certain constructions and combinations which will be hereinafter fully described and then specifically set forth in the claims hereunto appended.

In the accompanying drawings, which form a part of this specification and in which like characters of reference indicate the same or like parts:

Fig. 1 is a sectional side elevation of the entire banding mechanism;

Fig. 2 is a sectional plan view of the same;

Fig. 3 is a front elevation of the banding mechanism taken on line 9—9 of Fig. 1;

Fig. 4 is a sectional end elevation of the moistening device taken on line 10—10 of Fig. 1;

Fig. 5 is a detail plan view of the bander magazine;

Figs. 6, 7, 9 to 12 and 14 and 16 are detailed views in elevation of the operating parts in different positions, showing the successive steps in the operation of the banding mechanism;

Figs. 8, 13 and 15 are detail plan views of the preceding; and

Fig. 17 is a detail view of the conveyor chain.

Fig. 18 is a sectional side elevation of the transfer from the first conveyor or bander chain to the wrapper chain; Fig. 19 is an end elevation of the same taken on the line 19—19 of Fig. 18.

The various means referred to below may be varied widely in construction within the scope of the claims, for the particular device selected to illustrate the invention is but one of many possible concrete embodiments of the same. The invention therefore is not to be restricted to the precise details shown and described.

The bander provides in combination with a band magazine, a moistener, band applying device, a rotating suction unit and means for operating said unit to withdraw a band from the magazine, carry it to the moistener and from there to the band applier. Preferably said operating means includes mechanism for giving said unit a reciprocating movement toward and away from said magazine to withdraw a band therefrom and to move a band thereon into contact with the article to be banded.

Intermittently driven conveyor chains 132 (see Figs. 17, 18 and 19) are provided with sets of grippers 213 and 214 pivotally mounted thereon and held against the sides of cigars inserted therebetween by tension springs connecting the same. The conveyor chains move successive cigars into the range of action of the banding mechanism and then dwell while the band is applied. The banding mechanism is slidably supported by a bracket 254 (see Figs. 1 and 3) mounted to the rear frame of side frames 100. To bracket 254 is attached the housing 255 carrying and enclosing the drive of the banding mechanism. The latter is driven through a chain 257 driven from a shaft (not shown) and running over a sprocket 258 mounted on shaft 259 supported by bearings in bracket 254 and housing 255. The shaft 259 carries a bevel gear 260 meshing with a bevel gear 261 mounted on a vertical shaft 262. This shaft also carries a spiral gear 263 meshing with another spiral gear 264 on shaft 265 supported in bearings of the upper part 266 of housing 255.

To intermittently rotate the bander turret, a gear 264 (see Fig. 1) is equipped with a roller 267 actuating a Geneva wheel 268 mounted on shaft 269 carrying a gear 270 meshing with a gear 271 loosely mounted on shaft 272. To the latter is fastened a turret housing 273 supporting the turret shaft 274 to which is mounted the bander turret 275 for intermittent rotation. The turret shaft 274 carries a gear 276 which is actuated through an intermediate gear 277 from gear 271.

To give the turret movement, in addition to its rotation, to and from the band magazine and cigar, the housing 273 receives vertical recipro-

cating or rocking motion from shaft 272 being actuated for this purpose from a cam lever 278 engaging with roller 279 in cam track 270 of cam 281 mounted on shaft 265.

5 The arms of turret 275 are bored to provide air channels 282 (Fig. 3) and at their ends are equipped with suction heads 283 for retaining the bands. To the hub of turret 275 is attached a stationary air regulating head 284 which is connected by means of a tube 285 (Fig. 1) to a standard suction pump (not shown). The regulating head 284 is so constructed and set that it connects only three of the four air channels 282 of turret 275 because only three arms of turret 275 carry on their suction heads bands B to be applied to the cigar C, Fig. 8. The fourth arm from which the band B is taken again receives suction when it arrives underneath the bander magazine 286 to take another band B.

20 The band magazine 286 is provided with side walls which are adjustable to different sizes of bands by means of conical thumb screws 287. The band magazine is adjustably supported by a bracket 288 secured to the housing 266.

25 A band moistening device (Fig. 4) is provided for moistening the standard cigar bands which are gummed on one end, while the turret unit retains the band B on the band retaining arm's first stop after leaving the magazine 286 where the gummed end is moistened. The moistening device consists of a moistening wheel 289 equipped with a felt ring 290 which is moistened by the water M stored in a moistening pot 291, which is adjustably held by a bracket 292 fastened to main frame 100. The moistening wheel 289 is clamped to a shaft 293 supported by a bearing 294 of moistening pot 291. On the shaft 293 is mounted a ratchet 295 operated from a pawl 296 hinged to lever 297 which is fastened 40 to shaft 298 supported in bracket 292. On the shaft 298 is mounted a lever 299 connected through a rod 300 to a bell crank lever 301 pivoted to stud 302 secured to housing 266. The bell crank lever 301 is equipped with a roller 303 which is in engagement with a cam 304 mounted on shaft 265. The cam 304 gives a rocking motion to the bell crank lever 301 which also rocks pawl 296 thereby turning moistening wheel 289 and preventing the same from getting dry on the upper part.

In order to be assured that the gummed end of the band B is well moistened, a lever 305 presses the gummed end of the band B gently against the moistened felt ring 290 (Fig. 8). The lever 305 is pivoted to a stud 306 and is equipped with a gear segment 307 engaging with another segment 308 which is mounted on shaft 298, transmitting rocking motion received from cam 304 to lever 305.

60 On the next turn of the turret 285 the moistened band is taken to a position adjacent the cigar C which is conveyed by the chains 132. The turret 275 places the band B as a result of the reciprocating movement referred to, against the top side of cigar C and holds it there by suction and pressure thereby preventing displacement of the cigar during the folding of the band.

The side folds of the band B (Fig. 3) are made 70 by a pair of folding fingers 309 and 310 pivoted to a vertically sliding plate 311 slidably mounted in the front part of housing 266. The sliding plate 311 is equipped with a lug 312 carrying stud 313 to which is connected a link 314 pivoted to cam lever 315 having roller 316 which

engages in cam track 317 of cam 281. Cam lever 315 is pivoted with a stud 318 to housing 266. Cam lever 315 transmits its up and down motion to sliding plate 311 which controls the up and down motion of folding fingers 309 and 310. The latter are in engagement with each other by means of gear segments (Fig. 3) and therefore move equally. Finger 309 is equipped with a lever 320 carrying roller 321. When sliding plate 311 is in its upmost position, (Fig. 7), roller 321 rides against the stationary cam plate 322 thus causing fingers 309 and 310 to open. The latter are connected by a tension spring 323 to assure good control of the roller 321 against cam plate 322 held by studs 324 to the housing 266 and to assure a light, yielding pressure on the cigar regardless of size, the actual engagement with the cigar being by spring pressure alone.

Thus, while the mid portion of the band B is securely held between the turret 275 and the cigar C, the fingers 309 and 310 move downward by the sliding plate 311 and lay the band smoothly over the side of the cigar (Fig. 3). The roller 321 is then free and the fingers 309 and 310 are held together by the spring 323 to exert resilient pressure on the sides of the cigar and remain in this position until the bottom fold of the band B is made. This is important because it prevents any bulging of the sides or upper corners during laying of the band ends.

The first bottom fold or laying of the band end is made by a pair of bottom fold fingers 325 (Figs. 12 and 13) which are pivoted in a scissor-like manner to a guide plate 326 by means of pins 327 (Fig. 13). The guide plate 326 is pivoted to a stud 328 supported by plates 329 mounted to a guide head 330 slidably mounted on guide rods 331 held by bracket 332 attached to housing 255. Guide head 330 is equipped with a gear rack 333 operated from a gear segment 334 mounted on shaft 335 carrying another gear segment 336 (Fig. 1) meshing with a gear segment 337 pivoted on stud 338 supported by housing 255. Gear segment 337 is equipped with a cam lever 339 engaging with a roller 340 in one cam track of double cam 341 mounted on shaft 259. The above serves to give the finger movement transverse to and under the cigars and between and below the operating faces of grippers 213.

In order to prevent injuring the cigar and to assure a tight fold of the band, fingers 325, when advancing towards the cigar C (Fig. 11) are guided downward a little to clear the edge of the cigar and then immediately up again to continue their movement while pressing the cigar. This motion is created by an arm 342 attached to guide plate 326. Arm 342 is equipped with a roller 343, which rolls over a hump 344 on bracket 332. As soon as roller 343 leaves hump 344, a spring 345 mounted between guide plate 326 and guide head 330 presses fingers 325 firmly against the cigar C (Fig. 12) and assures a tight fold of the band B.

It will be noted that spring pressure alone 65 presses finger 325 against the cigar so it can fit itself to irregularities of the cigars. As soon as the first bottom fold is made a folding roller or band end laying element 346 (Fig. 12) advances towards the cigar C and folds or lays the other 70 end of the band B over the first folded end, (Fig. 14). The folding roller 346 is pivoted on a stud 347 supported by a forked guide shoe 348 pivoted by means of stud 349 to a supporting block 350 (Fig. 12), mounted on a guide head 351, slidably 75

supported by guide rods 331 and equipped with a gear rack 352 operated from a gear segment 353 mounted on a sleeve shaft 354 having another gear segment 355 (Fig. 1) meshing with gear segment 356 pivoted on stud 338. The segment 356 is equipped with a cam lever 357 engaging with roller 358 in the other cam track of double cam 341. Between supporting block 350 and guide head 351 is mounted a wedge shaped separating plate 359.

When the roller 346 advances toward the cigar C, the prow of cam plate 359 enters between two pins 360 mounted on fingers 325, which cause the latter to spread apart (Fig. 15) allowing just enough room to admit the roller between fingers 325 while the edges of the latter will still be holding the first folded end against the cigar. The roller 346 rolls the moistened gummed end of the band B over the first fold thereby sealing the band. In order to assure a good tight fold the guide shoe 348 supporting roller 346 is equipped with a spring 361 so that roller 346 will resiliently press the band firmly against the cigar C. By this means also the roller may yield to irregularities of the cigars. In order to assure the correct position of pins 360 against the prow of wedge shaped plate 359, fingers 325 are equipped with a spring 362 which also causes fingers 325 to close again upon the retreat of wedge plate 359. In order to keep fingers 325 parallel to guide block 326 a guide pin 363 is provided.

During the folding operation just described, the side fold fingers 309 and 310 remain in their closed position on the cigar; but as soon as the bottom fold is completed, fingers 309 and 310 release the cigar (Fig. 14) and move upward. The releasing of fingers 309 and 310 while in their lowermost position is caused by a star cam 364 (Figs. 2 and 14) mounted on turret shaft 274. A slight turn of the turret (see dotted position in Fig. 10) causes the engagement of star cam 364 with roller 365 on lever 320. Then turret 275 and fingers 309 and 310 on plate 311 move upward together to a position at which the other roller 321 on lever 320 engages with stationary cam plate 322. Turret 275 then resumes its rotation and star cam 364 leaves roller 365 and the fingers 309 and 310 are now held by roller 321 and cam plate 322.

After the band B is folded around the cigar C, conveyor chain 132 (see Fig. 17) continues its intermittent cigar forwarding movement and while fingers 325 go back to their original position, roller 346 remains on the band following the movement of the cigar for this purpose, and guides the cigar until it reaches the stationary guide plate 366 (Fig. 6), mounted on a lug of housing 255. As the cigar leaves banding position the band is guided and held on the cigar between the lower guide plate 366 and a leaf spring upper guide 367 to prevent loosening or springing up of the band ends and to give time for drying of the seal. The spring guide 367 is adjustably mounted on a bracket 368 fastened to housing 266.

The banded cigar C is then conveyed to a transfer device, (Figs. 18 and 19) where the cigar is transferred from the conveyor chain 132 in which the cigars were gripped during banding to a wrapper chain consisting of a number of individual pockets traveling intermittently in synchronism with the bander chain 132.

The chain 132 carries the cigar to one banding position where the banding operations are

carried on while the cigar is securely held towards either end by the laterally spaced gripper fingers 213 and 214 (see Fig. 17). The suction band turret 275 is given a bodily movement up against the bands in a magazine and then downwardly to withdraw a band and also to bring a band on the diametrically opposite turret arm into position on top of the cigar. A pair of flexible but pivoted and spring pressed fingers 309 come down along the radially extending turret arm, spaced apart more than the width of the cigar to pass the corners thereof. Then the fingers come together and lightly press toward the center of the cigar while continuing to move downwardly to fold the band. This results in a frictional sliding contact with the band and pulls the band tightly over the top and corners of the cigar, holding the band tightly folded over three sides of the cigar while the downwardly extending band ends are laid one over the other.

The band ends are folded against the bottom of the cigar by two fingers 325 and 348 one of which is split and moves first across the bottom of the cigar to lay one end and the other of which moves between the split portions to lay the other end while the split portions securely hold down the first end. This second finger travels with the cigar when it is indexed to the plate 366 to hold the band closed till engaged by the plate, acting as a bridge between banding position and the edge of the plate. The cigar is then transferred from the chain to the pockets of a wrapping chain, the cigar during the transfer being pushed into a sheet of wrapping material previously fed between the cigar and the pocket. However, the banding mechanism is a single unit which can be readily detached and replaced on another base where it will band after instead of before wrapping.

The transfer to the wrapper chain (Figs. 18 and 19), is supported by a bracket 369 mounted on a bearing bracket 370 supported by the frame. The supporting bracket 369 carries the two vertical guide shafts 373 to which is slidably mounted the transfer head 374, which is actuated through a link 375 from a suitable part of the mechanism.

The transfer head 374 carries a cam piece 383 (Fig. 18) actuating a roller 384 pivoted to a stud 385 supported by fork 386 to which is fastened a rod 387 slidably supported by a guide bearing 388 pivoted to stud 389 mounted in lugs 390. Rod 387 is equipped with a tension spring 391 placed between guide bearing 390 and fork 386 thereby pressing roller 384 towards cam piece 383. The fork 386 carries another horizontal shaft 392 to which are pivoted bell crank levers 393 pivoted to studs 394 mounted to lugs of the side frames (not shown). The transfer head 374 also carries on pivots 395 a pair of supporting levers 396 equipped with studs 397 to which are pivoted cigar gripping fingers 398 having each a lug 399 to which is pivoted a guide roller 400. These guide rollers are in constant engagement with a vertical camming and elevating shaft 401 slidably supported in transfer head 374. The engagement of rollers 400 with sliding shaft 401 is produced by a spring 402 mounted between fingers 398.

The distance between the two clamping fingers 398 can be adjusted to suit the diameter of the cigar by means of adjusting screws 403 placed in supporting levers 396. To the top part of shaft 401 is fastened a lifting plate 404 for engaging and elevating the cigar. The bottom

part carries a fork 405 through which shaft 401 is operated by a rod 406.

While the conveyor chains 132 which carry the banded cigars C, are in motion, the transfer head 8 374 is in its lowermost position (Figs. 18 and 19), so that the cigar can pass over clamping fingers 398 and lifting plate 404. In this position roller 384 is held back by cam piece 383 causing bell crank levers 393 to be out of the way of the 10 grippers on chains 132. As soon as the chain 132 stops its movement transfer head 374 goes upward causing roller 384 to leave cam piece 383. The rod 387 goes forward due to the tension of spring 391 thereby actuating bell crank 15 levers 393 in such a way that the upper free parts press against the extending ends 217 of the U shaped gripper fingers 213 and 214, the gear segments 218 of which are in engagement with gear segments 219 thereby opening the grippers. In 20 the meantime, shaft 401 has come up and met with its lifter plate 404, the cigar C. The clamping fingers 398 have also moved upward with the transfer head 374 and the rollers 400 in engagement with shaft 401 have left the lower thick 25 part of the same and in making contact with the upper thin part of the shaft 401, causes clamping fingers 398 to close and clamp the cigar C which then is transferred into the pockets of the wrapper chain, between walls 429. 30

It will be noted from the above (and Fig. 7) that during this transfer there is at all times a positive grip on the cigar. Even at the moment when the wrapper pocket walls 429 open to receive, and transfer fingers 398 open to release, 35 the cigar, said cigar is securely gripped from above and below by plunger 404 and tension plate 436.

What is claimed is:

1. The combination with a band magazine, of 40 band applying devices, a rotating band carrier, having spaced projecting band-retaining parts forming a fixed part of said carrier, and means operating said carrier to withdraw a band from the magazine and carry it to said applying devices, said applying devices including a pair of folders movable astraddle the cigar to contact the band and slide across opposite sides of the cigar to fold the band against said sides.

2. The combination with a band magazine, of 50 band applying devices, a rotating band carrier, having spaced projecting band-retaining parts forming a fixed part of said carrier, and means operating said carrier to withdraw a band from the magazine and carry it to said applying devices, said applying devices including a pair of folders movable astraddle the cigar to contact the band and slide across opposite sides of the cigar, to fold and then hold the band against said sides, and means for laying the ends of the band one over 55 the other while said folders are holding the side folds.

3. The combination with a band magazine, of 60 band applying devices, a rotating band carrier, and means operating said carrier to withdraw a band from the magazine and carry it to said applying devices, said carrier having spaced projecting suction band retaining parts forming a fixed part of said carrier.

4. The combination with a band magazine, of 70 band applying devices, a rotating band carrier, and means operating said carrier to withdraw a band from the magazine and carry it to said applying devices, said carrier having spaced projecting suction band retaining parts and said 75 means including mechanism giving said carrier

bodily movement to engage one of said parts with a band within the magazine.

5. The combination with a band magazine, of band applying devices, a rotating band carrier, and means operating said carrier to withdraw a band from the magazine and carry it to said applying devices, said carrier having a radially extending part for holding a band against the cigar, and said devices including a pair of folders on each side of said part movable radially thereof into engagement with the band, and means stationary relative to the unit for supporting said folders in spaced relation to permit rotary movement of said part between the same.

6. The combination with a band magazine, of 15 band applying devices, a rotating band carrier, and means operating said carrier to withdraw a band from the magazine and carry it to said applying devices, said rotating carrier having diametrically opposed band retaining devices, and 20 said means including mechanism for giving the axis of said carrier a movement toward a cigar to withdraw one band from the magazine with one retaining device while moving another band to the cigar with the other retaining device. 25

7. The combination with a band magazine, of band applying devices, a rotating band carrier, and means operating said carrier to withdraw a band from the magazine and carry it to said applying devices, said carrier having a radially extending part having a peripheral face for holding a band against a cigar, and said devices including a pair of folders, one on each side of 30 said part movable radially thereof into engagement with the band. 35

8. The combination with a band magazine, of band applying devices, a rotating band carrier, and means operating said carrier to withdraw a band from the magazine and carry it to said applying devices, said operating means including 40 mechanism for giving the axis of said carrier bodily movement toward and away from said magazine.

9. The combination with a band magazine, of band applying devices, a rotating band carrier, and means operating said carrier to withdraw a band from the magazine and carry it to said applying devices, a support for holding a cigar in the range of action of said devices, said means including mechanism for giving said carrier bodily 50 movement to move a band thereon into contact with a cigar on said support. 55

10. The combination with a band magazine, of band applying devices, a rotating band carrier, and means operating said carrier to withdraw a band from the magazine and carry it to said applying devices, said operating means including a pivoted arm rotatably supporting said carrier, and mechanism for oscillating said arm to give the axis of said carrier movement toward and away 60 from said magazine. 65

11. In a cigar banding machine, the combination with a cigar support, of means for locating a band across the cigar, a pair of folders, means for moving said folders toward the cigar and together to straddle the same and fold and press the band against the sides of the cigar, said devices including intermeshing gear segments connecting said folders for equal and opposite movement. 70

12. In a cigar banding machine, the combination with means for supporting a cigar, of mechanism for wrapping a band about three sides of the cigar with the ends outstanding, and means for laying said ends one over the other, comprising a first folder movable transversely of the cigar 75

5 to lay one end of the band against the cigar, a second folder movable in the opposite direction to lay the other end of the band over the first laid end, one of said folders being split, and means for parting the elements of the split folder to admit the other folder between them, while said split folder continues to hold the band end against the cigar.

10 13. In a cigar banding machine, the combination with means for supporting a cigar, of mechanism for wrapping a band about three sides of the cigar with the ends outstanding, and means for laying said ends one over the other, comprising a first folder movement transversely of the cigar 15 to lay one end of the band against the cigar, a second folder movable in the opposite direction to lay the other end of the band over the first laid end, one of said folders being split, and means for parting the elements of the split folder to 20 admit the other folder between them, said folders being provided with coacting cam elements to part the split folder parts.

25 14. In a cigar banding machine, the combination with means for supporting a cigar, of mechanism for wrapping a band about three sides of the cigar with the ends outstanding, and means for laying said ends one over the other, comprising a first folder movable transversely of the cigar to lay one end of the band against the cigar, a second 30 folder movable in the opposite direction to lay the other end of the band over the first laid end, one of said folders being split, and coacting means on the two folders for parting the split folder to admit the other folder, said means comprising a 35 prow shaped cam traveling with the unsplit folder, and means on each of the parts formed by the split folder arranged to be engaged by the cam passing between them to separate said parts.

40 15. In a cigar banding machine, the combination with means for supporting a cigar, of mechanism for wrapping a band about three sides of the cigar with the ends outstanding, and means for laying said ends one over the other, comprising a first folder movable transversely of the cigar to lay one end of the band against the cigar, a second folder movable in the opposite direction to lay the other end of the band over the first laid end, and means for directing one of said folders downwardly from the cigar prior to passing the 45 corner thereof.

50 16. In a cigar banding machine, the combination with means for supporting a cigar, of mechanism for wrapping a band about three sides of the cigar with the ends outstanding, and means for laying said ends one over the other, comprising a first folder movable transversely of the cigar to lay one end of the band against the cigar, a second folder movable in the opposite direction to lay the other end of the band over the first laid end, and a spring arranged to urge at least one of said folders against the cigar and a cam engaging an element on said folder in opposition to said spring to hold said folder away from the cigar as it clears the corner thereof, said spring operating to resiliently press the folder against the cigar during a remaining part of said transverse movement.

55 17. In a cigar banding machine, the combination with a band magazine, of a moistener, band applying devices, a rotating suction unit and means for operating said unit to withdraw a band from within the magazine and carry it to the moistener and then to the range of action of said applying devices to hold the band during at least 60 part of the operation of said devices, said apply-

ing devices including means for wrapping the band around the cigar and lapping the ends.

65 18. The combination with band applying means, of devices for rendering said band adhesive and a band turret having band retaining means, a band magazine, mechanism for operating said band turret to remove a band from said magazine, move it to a position where it is rendered adhesive by said devices and thence to said banding position where the band is retained by 70 said turret, said mechanism acting to intermittently rotate said turret, and said applying means having folders for folding the band about the cigar during a dwell in the rotation of said turret.

75 19. In a banding machine, the combination with a band magazine, of a cigar support, a plurality of spaced band retaining devices mounted for rotation about a common axis, means operating said devices to rotate the same from a position adjacent the magazine to a position adjacent the cigar support, and means for giving the said band retaining devices a movement independent of said rotation toward and away from the magazine to retain and withdraw a band, and mechanism for partially wrapping the band about the cigar on said support while the band is still retained by said device.

80 20. In a cigar banding machine, the combination with a support for a cigar in banding position, of a band magazine, a rotary band conveyor having means for retaining a band thereon, means for giving said conveyor a to and fro movement toward and away from the band magazine to engage and remove a band, means for rendering 85 the band adhesive, and means for rotating said conveyor to a position where the band is rendered adhesive by said means and then to said banding position.

90 21. The combination with an endless chain having opposed grippers thereon for gripping and transporting a plurality of cigars sidewise and along a straight line, of banding means coacting with said grippers to wrap bands in succession each around an individual cigar, and to lap the ends of each band, while the cigars remain in said grippers on said chain, said banding mechanism operating at a region of the cigar removed from said grippers, and including devices to compress the band in its applied position independently of said grippers.

95 22. The combination with a machine frame, of a cigar conveyor on said frame for conveying cigars sidewise and along a substantially straight path, of a banding unit cooperating with said conveyor to band a cigar thereon, said banding unit comprising a frame to one side of the conveyor, detachably secured to the conveyor supporting frame, means projecting laterally and downwardly from said frame to operate to act on 100 a band on the cigar from above, mechanism projecting laterally and upwardly from said unit frame to operate on a band on the cigar from the underside thereof, and operating devices connected both to said means and mechanism secured to 105 said unit frame.

110 23. In a cigar banding machine, the combination with devices for intermittently advancing a cigar, of mechanism for rendering one end of a cigar band adhesive and wrapping it about three 115 sides of a cigar in the range of action of said devices, means for lapping the ends of the band on the fourth side of the cigar including a folder for acting upon the last folded end of the band, and mechanism operating during advance of the 120

cigar after completion of the end lapping operation to give said folder a movement with the cigar to hold in position the freshly sealed band ends during part of said advance.

- 5 24. In a cigar banding machine, the combination with a cigar support, of a band holder, a rotating band carrier including means for transferring a band from said band holder to a band applying station, means for transferring a cigar on said support to said station, and band applying devices including a pair of folders, means for moving said folders toward the cigar and together to straddle the same and fold and press the band against the sides of the cigar, said folders comprising inflexible fingers, and said means including mechanism operating to cause the fingers to continue their folding movement after said fingers have moved together to press the sides of the cigar, and devices for lapping the ends of said band while said fingers press said sides.
- 10 25. In a cigar banding machine, the combination with a cigar support, of a band holder, a rotating bander turret including means for transferring a band from said band holder to a band applying station, means for transferring a cigar on said support to said station, and band applying devices including a pair of folders, means for moving said folders toward the cigar and together to straddle the same and fold and press the band against the sides of the cigar, said folders comprising inflexible fingers, and means including mechanism yieldingly moving said fingers together, and positive means for controlling the extent of the said movement of said fingers together.
- 15 26. In a cigar banding machine, the combination with a cigar support, of a band holder, a rotating bander turret including means for transferring a band from said band holder to a band applying station, means for transferring a cigar on said support to said station, and band applying devices including a pair of folders, means for moving said folders toward the cigar and together to straddle the same and fold and press the band against the sides of the cigar, said means including devices connecting said folders for equal and opposite movement.

27. In a cigar banding machine, the combination with means for supporting a cigar, of mechanism for wrapping a band about three sides of the cigar with the ends outstanding, and means for laying said ends one over the other, comprising a first folder movable transversely of the cigar to lay one end of the band against the cigar, a second folder movable in the opposite direction to lay the other end of the band over the first laid end, devices for urging at least one of said folders against the cigar as it moves transversely thereof, and means for then giving said transversely moving folder a movement away from the partially banded portion of the cigar prior to passing the corner thereof.

28. In a cigar banding machine, the combination with means for presenting cigars seriatim in a banding position, of a bander operating to apply a band to each of said cigars successively at said banding position, a table, and devices beyond said table for operating further upon said banded cigars, said means transferring each of the cigars in its turn from said banding position over said table to said devices for acting further upon the banded cigars, said means having members operating to maintain a positive grip on each cigar as it is brought to said banding position and at all times thereafter until and including delivery on said table.

29. In a cigar banding machine, the combination with a support for the cigar, of means for positioning a band adjacent to the cigar, a pair of band folders, means for moving said folders against the band and astraddle the cigar to bend the band about the cigar, mechanism for lapping and sealing the ends of the band beneath the underside of the cigar, and for holding the freshly sealed ends until firmly adhered, and devices for separating said folders while said sealed ends are so held by the lapping and sealing mechanism, thereby freeing each cigar from restraint by the folders after it is banded, and means to grip and hold said cigars independently of said folders.

JOSEPH A. NEUMAIR. 45
